New York, N. Y.

Application March 7, 1945, Serial No. 581,533

5 Claims. (Cl. 61—67)

(Granted under the act of March 3, 1883, as
amended April 30, 1928; 370 O. G. 757)

This invention relates in general to a method and apparatus for moving heavy unwieldy objects, and in particular to a method and apparatus for placing sliding ways under a ship to enable its launching.

When a ship is in condition for launching, sliding ways must be moved into position beneath the ship upon ground ways. The ground ways constitute the foundation upon which the ship rests as it slides into the water. They generally consist of parallel ramps on both sides of the keel running the full length of the ship and incline from bow to stern toward and into the water and slightly inward toward the keel of the vessel. The sliding ways generally consist of long sections solidly constructed of heavy timbers and generally weighing from twelve to twenty-five tons each. Twenty or more sections of such sliding ways are generally required for each launching operation, depending upon the size, length and tonnage of the ship.

Ordinarily the sections of sliding ways are stored in the vicinity of the bow of the ship until just prior to the launching. Prior to the launching operation sufficient shoring is removed to clear the ground ways. A section of the sliding ways is then swung by a crane or other suitable moving means onto rollers on that section of the ground ways extending from beneath the bow of the vessel.

Prior practice was to slide the section down the ground ways upon rollers until it was in position at the water's edge. The section was then pulled off the ground ways in toward the keel blocks by means of skids and chain hoists attached to clips welded upon the ship; then a heavy coat of grease was applied to that portion of the ground ways upon which the particular section was to reside, and the sliding ways were pulled back upon the greased portion by the same method. Succeeding sections would be similarly placed until the operation was completed.

Only that portion of the ground ways upon which the particular section being handled was to reside could be greased, as any further portion would be fouled in the handling of the next section of sliding ways. This method required a high expenditure of men, material and time, subject to frequent accidents occurring during the handling of the heavy sections in the confined spaces beneath the vessel.

An object of this invention, therefore, is to provide a new method and apparatus for moving sliding ways beneath a ship prior to its launching.

According to the present invention, the sections of sliding ways are raised above the ground ways and while in an elevated position are moved down the ground ways and over the greased portion. They are then lowered into place. As the sliding ways remain above the ground ways all the way during their travel beneath the ship from bow to stern the greasing operations do not have to be limited to the area to be covered by one section. The present invention further eliminates the necessity of welding clips or other attaching means upon the sides of the ship, heretofore necessary.

The invention may best be understood by reference to the accompanying drawings in which:

Figure 1 is a view of the assembled apparatus showing its position in relation to a cross-section of sliding ways and ground ways used in ship launching embodying this invention.

Figure 2 is a side elevation of one of the dolly and jack devices shown in Figure 1.

Figure 3 is a top plan view of the dolly and jack device shown in Figure 2.

Figure 4 is an end elevation of the dolly and jack device shown in Figure 2.

Figure 5 is a sectional view taken on the line 5—5 of Figure 4, and

Figure 6 is a sectional view taken on the line 6—6 of Figure 2.

Referring to the drawings in detail, Figure 1 shows ground ways 21, covered with a thick coating of lubricant, such as grease 22, upon which sliding ways 23 are superimposed. Lag bolts 24 having lifting eyes 25 are screwed into 35 the sliding ways. On either side of the sliding ways and resting upon the ground ways are parallel tracks 26 which extend the full length of the ground ways 21. Dollies 27 rest upon the tracks on either side of the sliding ways 23 and two transverse members 28 placed across the sliding ways are supported thereon. The two transverse members 28 are spaced apart and support hangers 29 having hooked ends 30. These hangers 29 have a threaded section 31 which engages a nut 32 resting upon a washer 33 which is supported by the transverse members 28. The hangers 29 are positioned so that the hooks 30 engage the lifting eyes 25 of the lag bolts 24.

Referring to the dollies 27 in detail, Figures 2 to 6, members 35 are sidepieces welded or otherwise secured to floor plate 36 to form a frame or chassis. Heavy metal wheels 37 having axles 38 are rotatively mounted upon the chassis by means of anti-friction bearings (not shown) and are held in place by suitable retaining means, such

as nuts 39. Guide members 40, shown as pieces of angle iron, are mounted upright upon the floor plate 36 and fixedly secured thereto. These guide members are additionally supported by braces 41, welded or otherwise secured to the outer walls of the guide members 40 and to the floor plate 36. Positioned within the guide members 40 are adjustable members 42 of the same shape as the said guide members (see Fig. 6). A head plate 43 is secured to the members 42, and is braced and strengthened by aprons 44 secured to the bottom of the head plate and to the edges of the members 42. The members 42, head plate 43 and aprons 44 form a movable head unit designated as 45.

The unit 45 may be raised or lowered vertically by means of a heavy duty jack 46, the base 47 of which rests upon the floor plate 36, and the head 48 of which engages the bottom of the head plate 43. The jack 46 is operated by means of a crank 49 into which a handle, or other suitable prime mover (not shown), may be inserted. Said crank 49 extends outwardly from the jack to an extent that the handle will clear the dolly when operated, best seen in Figure 4.

Upon one wheel of each dolly a driving mechanism therefor is provided. This mechanism consists of a ratchet wheel 50 solidly fixed to said wheel 37. A drive member 51 into which a handle 52 may be inserted is rotatively positioned on the axle 38 adjacent to the ratchet wheel 50. A pawl 53 having a lip 54 is rotatively fixed as at 55 to the inner side of the drive member 51 and above the ratchet wheel 50 and is so positioned that the lip 54 engages the teeth of said ratchet wheel. As the handle 52 is moved down the lip 54 of the pawl 53 slides over the teeth of the ratchet wheel. As it is moved up the lip 54 engages the teeth of the ratchet wheel and causes both ratchet wheel 50 and the wheel 37 to rotate (see Figure 5).

A brake device is also provided to control the movement of the dolly upon the groundways. This device consists of a frame 56 secured to the sidepieces 35 and tapering above the wheel 37 to an internally threaded collar 57. A screw 58 operated by a hand wheel 59 threadedly engages said internally threaded collar 57. A brake shoe 60 is coupled to the end of the screw 58 and is positioned above the face of the wheel 37. By turning the brake wheel 59 the brake shoe 60 may be forced against the wheel 37 providing a powerful braking action.

In operation, a section of sliding ways is placed by a crane or other means on the lubricated ground ways at the bow of the ship between the track 26. Dollies 27 are placed on each of the tracks directly opposite each other. Lag bolts 24 are screwed into the section. Transverse members 28 are placed across the section and on the movable heads 45 of the dollies, and each assembly, consisting of two dollies with the two transverse members resting upon them, is lined up with the lag bolts 24. If desired the transverse members 28 may be fixed to the movable heads 45 of the dollies, however, the weight of the members alone will hold the assembly together. The hangers 29 are now placed upon the transverse members and moved between the bars and adjusted by means of nuts 32 until the hooks 30 engage the eyes 25 of the lag bolts. Two or more assemblies, spaced so as to evenly distribute the weight of the section are placed in the same manner.

The jacks 46 are now operated so as to raise the movable heads 45 of the dollies. By this

means the whole section of sliding ways is raised and swings beneath the transverse members. The section is now started down the inclining ground ways by operating the driving mechanisms on the dollies. After the section has started moving it will continue down the ground ways due to its own momentum. The dollies run smoothly on the tracks 26.

If the forward motion of the section down the ground ways becomes too great it may be necessary to slow it down, and if conditions require such, to bring it to rest. This is done by rotating the brake wheels 59 resulting in tightening the brake shoes 60 against the wheels 37 of the dollies, and a reverse operation to free the section for further motion, as conditions may require.

Prior to placing the required number of sections of sliding ways, it will be understood that any desired portion of the ground ways may be initially greased. After the section of sliding ways has been coasted into position over and above the greased ground ways and has been stopped and located, it is lowered upon the grease by lowering the jacks 46 on the dollies. The hangers 29 are disengaged from the lag bolts 24 and each assembly, consisting of the two dolly and jack devices 27 with the two transverse members 28 resting upon them, is rolled back up the inclining ground ways and over the next section of sliding ways which has meanwhile been placed on the ground ways at the bow. Each section is placed in the same manner.

By the above described method and apparatus, sliding ways are quickly and easily placed beneath a ship about to be launched. The welding of heavy clips to the ship for rigging operations and the dangerous practice of moving the sliding ways from the ground ways, greasing the ground ways, and then moving the sliding ways back over the greased portion, all in the confined space beneath the ship, have been eliminated. Greasing operations may be carried on at remote portions of the ground ways while the sections of sliding ways are being placed, and any desired portion of the ground ways may be greased beforehand. Time, labor and accidents in the placing of sliding ways have been greatly reduced.

It is to be understood that various modifications and changes may be made in this invention without departing from the spirit and scope thereof, as set forth in the appended claims.

The invention described herein may be manufactured and used by or for the Government of the United States of America for governmental purposes without the payment of any royalties thereon or therefor.

What is claimed is:

1. The method of placing sliding ways beneath a ship upon ground ways comprising, applying a coating of grease to said ground ways, placing a section of sliding ways upon the said ground ways at the bow of the ship, raising said section of sliding ways above the level of the said ground ways, moving the said section of sliding ways down the ground ways beneath the ship while said section of sliding ways is in an elevated position, and lowering said section of sliding ways upon the grease on said ground ways when the said section of sliding ways is in proper position beneath the ship.

2. The method of placing sliding ways beneath a ship upon ground ways comprising, applying a coating of grease to a portion of said ground ways beneath the ship, placing a section of slid-

ing ways upon the said ground ways at the bow of the ship, raising said section of sliding ways above the level of the said ground ways, moving the said section of sliding ways down the ground ways beneath the ship and over the greased portion of said ground ways while the said section of sliding ways is in an elevated position, and lowering the said section of sliding ways upon the grease on said greased portion of ground ways.

3. An apparatus for placing sliding ways beneath a ship upon ground ways comprising parallel tracks extending substantially the length of said ground ways a transverse member positioned across said tracks, means upon said transverse member for securing said sliding ways thereunder, and rolling means positioned at approximately each end of said transverse member and resting upon said tracks, each of the said rolling means having a movable member and means for raising and lowering the said movable member, and the said transverse member being supported at each end by the said movable members of the said rolling means.

4. An apparatus for placing sliding ways beneath a ship upon ground ways comprising, parallel tracks extending the length of the said ground ways, said tracks being spaced apart at

least the width of said sliding ways, a transverse member positioned across said tracks, and rolling means positioned at approximately each end of said transverse member and resting upon said tracks, each of the said rolling means having a movable member and means for raising and lowering said movable member, and the said transverse member being supported at each end by the said movable members of the said rolling means.

5. An apparatus for placing sliding ways beneath a ship upon ground ways comprising parallel tracks extending the length of the said ground ways, said tracks being spaced apart at least the width of said sliding ways whereby a section of sliding ways may be placed between the said tracks, a transverse member positioned across said tracks, a chassis having wheels rotatively mounted thereon, positioned at approximately each end of said transverse member, the said wheels resting upon the said tracks, each of the said chassis having a movable member and means for raising and lowering the said movable member, and the said transverse member being supported at its ends upon the said movable members.
